UNITED STATES PATENT OFFICE.

OLE PETERSON, OF CLEVELAND, OHIO.

STITCH-PICKING DEVICE.

Application filed February 20, 1926. Serial No. 89,525.

My invention relates to an improvement in 5
stitch pickers, my object in general being to
provide a rotary tool for shoe finishing or
repairing machines, whereby the stitches in
the sole of a shoe may be picked cleanly
and rapidly without injury to the welt or
shoe upper, preparatory to repairing or re-
soling operations.

In the accompanying drawings, Fig. 1 is
10 a front elevation on a reduced scale, of a
shoe finishing machine having my improved
stitch picking tool affixed to a spindle or
shaft therein. Fig. 2 is an enlarged eleva-
tion, and Fig. 3 a sectional view, of my
15 rotary picker and a shoe. Fig. 4 is a sec-
tional detail of a part of the picker, on a
larger scale than actual size; and Fig. 5
is a similar view of a modification.

As a preliminary step in renewing a
20 stiched sole the stitches which secure the
welt and sole together are first cut by in-
serting a knife between the welt 2 and sole
3. The loop stitches S in the welt may then
25 be picked out by pressing the welt upwardly
against the periphery of my rotary picker.
A while shifting or turning the shoe along
the line of stitches in the welt. Picker A
comprises a metal disk having a flat inner
30 side 4, a reduced round hub 5, and a conical
outer side or surface 6 curving on concave
lines toward flat side 4 to produce a narrow
or relatively sharp peripheral edge 7. A
central opening 8 extends through hub 5, and
35 this opening may contain a spiral groove or
screw-thread 9 whereby the disk may be se-
cured to the screw-threaded extremity or
spindle 10 of a rotatable shaft 11, such for
example, as used in a shoe finishing machine
40 B of the type delineated in Fig. 1. Con-
caved surface 6 permits the sewed portion 12
of the shoe upper 14 to be brought very
closely to peripheral edge 7, and accordingly
this edge may be caused to bear rotatably
45 against welt 2 at an intermediate point be-
tween the outer stitches S for sole 3 and the
sewed portion 12 of the upper. In this way
the upper may be pressed back or away from
stitches S and pressure brought to bear on
50 the welt by peripheral edge 7, it being under-
stood that the welt and sole as well as the
upper are yielding and flexible in varying
degree. As a result the stitches S are
brought into contact with a series of picking
55 teeth 15 forming part of a flat ratchet plate

16 sleeved over hub 5 and detachably secured
to flat side 4 by screws 17. Teeth 15 are
angular or like ratchet teeth, except that the
transverse scraping or picking edge 18 of
each tooth is curved and slants away from
60 peripheral edge 7 toward the axis of the
tool. A rounded corner or point 19 may also
be formed in each tooth 15 contiguous to the
periphery or circular edge 7 so that no sharp
cutting edges may be present in pressing the
65 welt toward the rapidly revolving teeth
which pick out the stitches successively as
the shoe is pressed in running engagement
with the disk or wheel.

In Fig. 5 I show a series of thin ratchet
70 plates 20 of different diameters having cor-
responding picking teeth 15' in stepping re-
lation, together with a clamping plate 21
and a clamping screw 22, extending through
curved slots 23 in the plates. In this form
75 of the device the plates or laminations 20-75
may be variously assembled to change the
outline of the picking edge, formed by the
contiguous teeth. The curved slots 23 in
the plates are concentric with the axis, and
80 therefore variable radial settings of the re-
spective plates and their teeth may also be
obtained.

What I claim, is:

1. A stitch picking device, comprising a
metal disk having a round hub portion
adapted to be connected detachably to a ro-
tatable shaft, one side of said disk being of
conical form curved on concave lines and
the opposite side being flat to form a flange
85 of gradually tapering thickness terminating
in a narrow peripheral bearing and guard-
ing edge, and a flat ring-shaped plate sleeved
over said hub portion and secured detach-
ably to the flat side of said flange having at
90 its periphery picking teeth, each tooth be-
ginning with a rounded corner contiguous
to said narrow peripheral edge and slant-
ing away therefrom toward the axis of the
device, said rounded corner of each tooth
95 projecting beyond said peripheral edge.

2. A stitch picking device as called for in
claim 1, made of a series of thin flat ring-
shaped plates of different diameter arranged
in stepped relation to form stepped pick-
ing edges.

In testimony whereof I affix my signature.

OLE PETERSON.
